Charles E. Brainard Attn:

UNITED STATES PATENT OFFICE

CHARLES E. BRAINARD, OF CHICAGO, ILLINOIS, ASSIGNOR TO WESTERN FOUNDRY COMPANY, OF CHICAGO, ILLINOIS, A CORPORATION OF ILLINOIS

PULVERIZER

Application filed August 2, 1928. Serial No. 296,924.

It is an object of this invention to provide an improved type of pulverizing machine of the rotatable type wherein material to be pulverized is adapted to be fed inwardly from both the feeding end and the discharge end of the machine into the field of operation of a plurality of passaged segmental roller sections and material distributing rings adapted to coact with one another and with the walls of the rotatable housing to grind and pulverize said material with said rings acting to carry the material from the bottom of the housing and deposit the same between the coacting segmental roller sections.

It is also an object of this invention to provide a pulverizer having a rotatable housing within which grinders consisting of segmental roller sections are loosely positioned in coacting interfitting relation with recessed rings to permit a proper distribution of the material within the housing to cause the segmental roller sections to thoroughly and efficiently pulverize material fed into the housing.

It is a further object of this invention to provide a pulverizing machine having a rotatable lined housing and, furthermore, having loosely positioned therein a plurality of passaged tapered roller segments arranged in groups with said groups separated by loose peripherally recessed rings adapted to carry the material accumulated in the bottom portion of the housing upwardly into the upper portion of the housing to be redistributed over said tapered roller segments to be further subjected to the pulverizing action of said segments.

It is furthermore an object of this invention to provide an improved pulverizing machine wherein a rotatable housing is adapted to enclose a plurality of loose rollers each constructed of a plurality of component interfitting passaged segments, certain faces of each of which are adapted to coact with an impact action and a shifting action with corresponding faces of the remaining segments, while the tapered or beveled side surfaces of the segments are in coacting interfitting relation with chambered rings adapted during the rotation of the housing to carry

the material from the lower portion of said housing upwardly to be redeposited between the segments for further pulverization.

It is an important object of this invention to provide a pulverizer of the rotatable housing type with rollers constructed of passaged segments having beveled side surfaces permitting the rollers to have interfitting frictional contact with the inner peripheral beveled surfaces of loose ring members having pockets in the outer peripheral surface thereof to permit redistributing of the material within the housing to subject the material to the repeated action of said rollers.

Other and further important objects of this invention will be apparent from the disclosures in the specification and the accompanying drawings.

This invention (in a preferred form) is illustrated in the drawings and hereinafter more fully described.

On the drawings:

Figure 1 is a longitudinal section of a pulverizer embodying the principles of this invention, showing improved segmental rollers in elevation and in engagement with improved ring members shown in section.

Figure 2 is an end elevation of the discharge end of the pulverizer.

Figure 3 is a transverse section of the housing taken on line III—III of Figure 1, illustrating the distributing action of the material by the ring members.

Figure 4 is a fragmentary longitudinal view of the interior of the housing, with said housing shown in section to show the coacting rollers and rings in elevation.

Figure 5 is a side elevation of one of the improved ring members removed from the housing.

Figure 6 is a peripheral view of the ring member.

Figure 7 is a diametric section of the ring member.

Figure 8 is a sectional view of a ring member taken on line VIII—VIII of Figure 6.

As shown on the drawings:

Supported on a base or foundation 1, are a pair of bearing standards or supports 2 and 3, between which a rotatable sectional hous-

ing or casing 4 is disposed. Integrally formed axially on one end of the housing section is a hollow entrance sleeve or supporting cylinder 5 having an opening 6, in the outer end thereof. Integrally formed on the inner peripheral wall of the supporting cylinder 5 is a spiral feed vane 7 adapted to feed a material from the outer end of said cylinder inwardly into the pulverizing chamber of the housing 4. Integrally formed axially on the opposite end of the housing section is a bearing sleeve or supporting cylinder 8 through which the pulverizing material is adapted to be discharged.

The outer end of the discharge cylinder 8 is provided with an outlet or discharge opening 9. Formed on the inner peripheral wall of the discharge cylinder 8 is a spiral vane or feed screw 10 arranged to permit any relatively heavy material that may find its way into the cylinder 8 to lodge behind the spiral vane 10 and be fed or carried back into the pulverizing chamber of the housing 4.

The apertured or discharge end of the supporting cylinder 8 projects into a stationary discharge drum or casing 11 which is supported upon the base or foundation 1, by means of supporting legs 12, or other suitable means. Formed on the bottom of the outlet casing 11 is a discharge sleeve or pipe 13 through which the granular product is adapted to be discharged into any suitable container or conveyor positioned beneath or connected with the discharge pipe 13. Connected with the upper end of the casing or drum 11 is a pipe 14 which is adapted to be connected with an air exhaust fan or water pump to induce a draft of air or steam through the pulverizing machine whereby the dust may be separated from the granular product and carried upwardly through the pipe 14 into a suitable dust container connected therewith.

Secured upon the discharge cylinder 8 between the bearing 2 and the housing 4, is a large gear wheel 15 with which a driving gear or pinion 16 is in mesh. The driving gear is secured upon a driving shaft 17, one end of which is journalled in a bearing 18 supported on an extension of the bearing standard 2. The other end of the driving shaft 17 is journalled in a bearing housing 19 supported by means of a standard 20 upon the opposite end of the base 1. Engaged on the other end of the shaft 17 to the outside of the bearing housing 19 is a driving pulley 21 adapted to be connected by means of a driving belt with any suitable source of driving power.

Mounted on the driving shaft 17 adjacent the inner end of the bearing housing 19, is a flanged pulley 22 around which a belt 23 is trained. The belt 23 is also trained around a second pulley 24 forming a part of a material feed mechanism. The pulley 24 is

mounted on the outer end of a shaft 25 which projects longitudinally through a material conveyor trough 26 supported upon a framework 27 secured to the top of the base section 1. A discharge chute or mouthpiece 28 is secured on the inner open end of the trough 26 and projects through the opening 6, into the receiving end of the bearing cylinder 5 of the pulverizing machine. Mounted on the shaft 25 near the discharge end of the trough 75 is a single-turn conveyor screw or blade 29. Supported above the conveyor trough 26 is a material feed hopper 30 provided with a false 80 slideable bottom 31 having a discharge opening 32 therein to permit material from the hopper to be admitted into the conveyor trough 26 at different distances from the feed screw 29, thereby affording an arrangement whereby the amount of material admitted into the feed trough may thus be 85 gradually advanced or piled up therein by which arrangement the feed of the material may be increased from a small amount until the full capacity of the feed screw 29 has been attained. This wide range of the feed- 90 ing of the material is obtained as stated, by shifting the false hopper bottom 31 so that the material entering from the hopper 30 into the feed trough 26 is piled up with the advance face of the pile of material assuming 95 an inclination of approximately thirty degrees, with the more finely crushed material usually in repose at the advance end of the pile of material so that the nearer the hole of the hopper bottom 31 is to the feed screw 29, the greater will be the amount of material which is brought into engagement with the revolving feed screw.

It will thus be seen that the amount of material to be pulverized or granulated may 105 be fed into the entrance end of the bearing sleeve 5 in predetermined or regulated amounts and advanced into the field of operation of the spiral feed screw or vane 7 which 110 advances the material into a grinding or pulverizing chamber 33 provided within the housing 4.

Rigidly secured to the tapered or inclined inner end walls of the housing 4, are dished or beveled bearing rings 34 which are constructed of hardened steel or any other suitable refractory material. The liner rings 34 are removably held in place so that when the same become worn new rings may be substituted in place thereof.

Loosely mounted within the crushing or pulverizing chamber 33 of the housing 4, are a plurality of floating grinders or roller mechanisms which have no connection with the interior of the housing or the liner rings 115 thereof, except as a result of the effect of gravity. Each of the grinders or rollers is constructed of hardened steel or other suitable material, and comprises a plurality of sections of segments 35 of substantially one hun- 120 dred weight.

dred twenty degrees, and are formed substantially as illustrated in Figures 1 and 3, with each segment having a flat middle peripheral surface 36 and two inclined or beveled peripheral side surfaces 37 positioned on opposite sides of the middle peripheral surface 36. Each segment 35 also has two angled surfaces 38, and is furthermore provided with a passage 39 extending from one of the surfaces 38 to the middle peripheral surface 36, and substantially parallel to the second angled surface 38. The outer end of the passage 39 is enlarged at the end opening through the middle peripheral surface 36.

15 The segmental rollers or grinders are arranged adjacent one another as illustrated in Figure 1, and each pair of said rollers is separated by means of an improved hardened steel ring 40 provided with inner peripheral beveled surfaces 41 which form a V cross-sectioned ring, the beveled surfaces 41 of which are adapted to have a slidable fit with the beveled side surfaces 37 of the sections forming the pair of adjacently positioned rollers. By referring to Figure 1, it will be noted that the segmental rollers interfit the beveled rings 40. Formed in the periphery of each of the rings 40 are a plurality of pockets or scoops 44 each of which is provided with a tapered discharge 20 opening 42, opening through one of the beveled inner peripheral surfaces 41 of the ring. The discharge openings 42 formed in the beveled inner peripheral surfaces of the ring are staggered with respect to one another. Each 25 of the pockets or scoops 44 formed in the outer periphery of the ring is provided with an inclined wall 43 which leads to the discharge opening 42 and serves as a guide for conducting any material caught in the pockets 44 out through the discharge opening 42 to be deposited between segments of the rollers for pulverization.

As illustrated and described, each of the weighted and hardened roller mechanisms 30 comprises three segments which, when placed together with the inclined surfaces 38 engaged with those of the adjacent segments, a substantially circular roller is formed of approximately three hundred sixty degrees. 35 In the present instance, there are three segment rollers disposed adjacent one another within the housing 4 affording V cross-sectioned circular grooves between the rollers for the reception of the V cross-sectioned rings 40. The adjacent sides of each pair of segment rollers are adapted to abut one another, and the beveled surfaces 37 thereof are adapted to have frictional contact with the beveled inner peripheral surfaces 41 of the 40 rings 40. The segmental rollers are loosely disposed within the housing 4 and are adapted to be rotated therewith, together with the rings so that the various segments comprising each roller will coact with one another not only with a hammer action between the

inclined surfaces 38, but also with a longitudinal or transverse frictional sliding movement as well as a radially sliding movement, thereby thoroughly crushing and pulverizing materials caught between the roller segments. 45 The segments of each roller not only act one upon the other, but each of said segments coacts with the hardened liners 34 and the inner peripheral surface of the main portion of the housing 4, to further crush and pulverize materials caught between the outer surfaces of the roller segments and the inner faces of the liners 34 and the housing 4. Attention is also called to the fact that there is an additional crushing and pulverizing action which 50 takes place between the beveled end surfaces 37 of the roller segments which coact with the beveled surfaces 41 of the rings 40. The crushing and pulverizing action produced in this improved machine, therefore, takes place 55 between the various segments of the rollers between the roller segments and the inner surfaces of the housing and between the coacting beveled surfaces of the roller segments and the material distributing rings 40.

During the operation of the machine, material which is partly crushed finds its way into the lower portion of the housing and, ordinarily, would be inclined to remain in the lower portion of the revolving housing 60 if it were not for the fact that the improved pocketed rings positioned between the rollers served as a means for carrying the material upwardly into the upper portion of the housing to be distributed between the roller segments and the rings.

During the rotation of the housing 4, the rings being loosely disposed within the housing, take on a rotatable motion and the pockets 44 of the rings pick up quantities of the material in the lower portion of the housing gradually carrying the same upwardly into a position illustrated in Figure 4, wherein the material is guided outwardly and slides over the inclined guide walls 43 and is discharged out of the discharge openings 42 between the roller segments and between said segments and the inner surface of the upper portion of the housing. The material within the lower portion of the housing is also adapted to be scooped up into the enlarged outer ends of the segment passages 39 (Figure 3), and is consequently carried upwardly until the roller segments reach the upper portion of the housing wherein the passages 39 assume an inclined position so that the lower or inner open end of the passage allows the material trapped in the passage to slide therethrough and be discharged into the space afforded between two of the separated segments as illustrated in Figure 3. It will be noted that both the material distributing rings and the 100 grooves within the roller segments serve to 105 110 115 120 125 130

repeatedly redistribute the material within the rotating housing so that said material is uniformly crushed and pulverized to any degree desired.

Attention is also directed to the fact that the outer peripheral surfaces of the various roller segments have a rolling or rubbing contact with the inner surfaces of the housing as well as a slidable rubbing action there-
with. In addition to the above pulverizing action between the parts, attention is also called to the fact that the outer peripheral surfaces of the material distributing rings also have a rolling and rubbing contact with the inner surface of the housing 4, to cause an additional crushing and pulverizing action to take place on the material. A de-
cided attrition or abrasive action both cen-
trifugally and longitudinally between the
segments of the crushing rollers, between the
roller segments and the inner surfaces of the
housing and between the beveled surfaces
of the segments and the rings, as well as the
peripheral surfaces of the rings and interior
of the housing, takes place thereby provid-
ing a highly efficient pulverizing machine
acting on materials fed by the feeding
mechanisms into the entrance bearing cylin-
der 5 and continuously redistributed due to
the action of the pocketed rings and the ef-
fect of the passages provided in the roller
segments.

A draft is adapted to be induced by air or steam through the pulverizing machine due to the connection of the pipe 14 with a suction pump or the like so that the pul-
verized or granular material crushed in the
chamber 33 will be drawn through the dis-
charge bearing cylinder 8 with the finely
pulverized material or dust being carried
upwardly through the pipe 14, while the
granular product is adapted to be dis-
charged through the discharge or outlet pipe
13.

Any material which is relatively heavy
and is not completely crushed or pulverized
which finds its way into the discharge cylin-
der 8 lodges behind the spiral blades or ribs
10 and due to the rotating action of the hous-
ing and its bearing cylinders will be fed
backwardly through the cylinder 8 to re-
enter the pulverizing or crushing chamber
33 to be further acted upon and completely
crushed or pulverized.

While the passaged segmental rollers are
illustrated as each comprising three inter-
fitting and coacting segments, it will, of
course, be understood that crushing rollers
constructed of any desired number of co-
acting segments may be furnished and that
the shapes of the segments may also be
varied without departing from the prin-
ciples of this invention.

I am aware that many changes may be
made and numerous details of construction

may be varied through a wide range with-
out departing from the principles of this
invention, and I therefore do not purpose
limiting the patent granted hereon, other-
wise than necessitated by the prior art.

I claim as my invention:

1. A pulverizer comprising a rotatable
housing having a crushing chamber therein,
means for feeding material into said housing,
a plurality of passaged coacting roller seg-
ments loosely mounted within the housing
adapted to coact with one another and with
the housing to crush and pulverize the mate-
rial fed into the housing, material distrib-
uting rings mounted within said housing in
coacting relation with said roller segments
to assist in the pulverizing action of the ma-
terial, and means connected with the housing
to withdraw the pulverized and granular
material therefrom.

2. A pulverizing machine comprising a ro-
tatable housing, means for supporting the
same, feed means for delivering a material
into the housing, and a roller mechanism
loosely mounted in said housing and com-
prising a plurality of coacting segments hav-
ing material distributing passages therein,
said segments adapted to coact with one an-
other with a sliding and an impact action
and further adapted to coact with the cas-
ing with a sliding and impact action to
crush and pulverize material fed into the
housing and distributed therein due to the
passage of material through the passages in
said segments and out through the coacting
surfaces of said segments.

3. A pulverizer comprising a housing,
means for rotating the same, and rollers
loosely mounted therein each comprising a
plurality of coacting segments adapted to
have a longitudinal and a radial sliding move-
ment with respect to one another in addition
to impact actions one on the other to cause
crushing and pulverizing of materials be-
tween the roller segments and between said
segments and the housing, said roller seg-
ments having passages therein permitting the
material to be circulated through the seg-
ments out through the coacting faces thereof
and repeatedly redeposited between the seg-
ments to cause further pulverization of the
material.

4. The combination with a rotatable pul-
verizer housing, of a roller loosely mounted
therein and comprising a plurality of pas-
saged roller segments constructed to have a
sliding and an impact action one with the
other and with the interior of the housing
to cause crushing and pulverizing of a mate-
rial deposited in the housing, and further-
more causing a distribution of the material
from between the roller segments and the cas-
ing by the discharge of the material through
the flat coacting faces of said passaged roller

- segments into the spaces between said segments.
5. The combination with a rotatable pulverizer housing, of rollers mounted therein each comprising a plurality of coacting passaged segments constructed to tumble around within the housing when the same is rotated so that said segments will have a sliding as well as an impact action one on the other and on the interior of the housing to crush and pulverize the material deposited in the housing, and further adapted to cause a circulation of the material through the segment passages by the discharge of the material through the openings in the coacting surfaces of the segments to repeatedly bring the material into the field of operation of said segments.
- 10 6. A pulverizer comprising a rotatable housing, hollow bearing cylinders for supporting the same, feed means mounted within said bearing cylinders to feed material into the housing from opposite directions, passaged segmental rollers loosely mounted adjacent one another within the housing arranged to discharge material through the coacting faces of the rollers, and material distributing rings positioned between said segmental rollers and coacting therewith to aid in the crushing and pulverizing of the material.
- 15 7. A pulverizer comprising a housing, means for feeding material into the housing from opposite directions, a plurality of passaged segmental rollers loosely mounted within said housing, and a plurality of material distributing rings loosely mounted within said housing between said segmental rollers.
- 20 8. A pulverizer comprising a rotatable housing, a plurality of segmental rollers loosely mounted within the housing adapted to coact with the housing to crush a material fed thereto, and ring members loosely mounted within said housing between said segmental rollers and having pockets therein, to permit the material within the housing to be redistributed for repeated pulverization by said segmental rollers.
- 25 9. The combination with a rotatable pulverizing housing, of passaged segmental rollers loosely mounted therein to coact with the housing by the action of gravity and the rotation of the housing to crush a material by attrition, said rollers having the passages arranged to cause discharge of material through the flat coacting surfaces of said rollers.
- 30 10. The combination with a pulverizing machine, of a roller mechanism adapted for use therein comprising a plurality of beveled roller segments having passages therein and adapted to interfit one with another to form a substantially complete roller, with the passages arranged to permit discharge of the
- material through the flat coacting surfaces of said segments.
11. The combination with a pulverizing machine, of passaged segmental beveled rollers mounted therein, and means loosely mounted within said housing for redistributing the material into the field of operation of said segmental rollers.
- 70 12. The combination with a rotatable pulverizing machine housing, of material distributing members loosely mounted therein, and segmental rollers within said housing for pulverizing the material distributed by said distributing members.
- 75 13. The combination with a rotatable pulverizing housing, of ring members loosely mounted therein and provided with pockets to permit a material within the housing to be circulated therein, and a plurality of passaged roller segments loosely mounted within said housing for coaction with one another, with the housing, and with said ring members to produce a thorough pulverization of the material.
- 80 14. The combination with a rotatable pulverizing housing, of passaged segmental rollers mounted therein, and material distributing rings within said housing between said segmental rollers with each of said distributing rings having a plurality of radial pockets adapted to distribute material from opposite sides of the ring members.
- 85 15. The combination with a rotatable pulverizing housing, of pulverizing rollers mounted therein, and material distributing rings loosely mounted within said housing to distribute the material into the field of operation of said rollers.
- 90 16. The combination with a rotatable pulverizing housing, of pulverizing members loosely mounted therein, and material distributing members loosely mounted within said housing in coacting relation with said pulverizing members.
- 95 17. The combination with a rotatable pulverizing housing and the pulverizing members thereof, of material distributing rings loosely mounted within said housing.
- 100 18. The combination with a rotatable pulverizing housing and the pulverizing members thereof, of material distributing members loosely mounted within said housing and having pockets therein with the outlets of said pockets staggered with respect to one another to permit material carried by said distributing members to be distributed from opposite sides thereof.
- 105 19. The combination with a pulverizing housing, of a material distributing member loosely mounted therein and comprising a ring having peripheral material conveyor pockets therein provided with outlet openings, and with inclined material guide walls to facilitate distribution of the material carried in said pockets.
- 110 120 125 130

20. The combination with a pulverizing housing, of passaged beveled rollers loosely mounted therein, and beveled rings loosely mounted in said housing between said rollers, 5 with each of said rings having peripheral material carrying pockets formed therein with the discharge openings of said pockets staggered to permit the material carried in said pockets to be distributed from opposite 10 sides of the rings.

20. In testimony whereof I have hereunto subscribed my name.

CHARLES E. BRAINARD.
